SLIP FIT COUPLER OR THE LIKE

John H. Hosking, Cincinnati, Ohio, assignor to John H. Hosking Co., Cincinnati, Ohio, a corporation of Ohio

Filed Oct. 6, 1958, Ser. No. 52,886

Term of patent 14 years

(Cl. D91—3)

Fig. 1

Fig. 2

Fig. 3

Fig. 4

Fig. 5

Fig. 6

Fig. 1 is a perspective view of a slip fit coupler or the like showing my new design;

Fig. 2 is an elevational view of the right end of the coupler as shown in Fig. 1;

Fig. 3 is an elevational view of the side of the coupler opposite that shown in Fig. 1;

Fig. 4 is an elevational view of the end of the coupler opposite that shown in Fig. 2; and

Figs. 5 and 6 are top and bottom plan views, respectively, of the coupler as shown in Fig. 4.

I claim:

The ornamental design for a slip fit coupler or the like, as shown.
